UNITED STATES PATENT OFFICE.

ROBERT G. WEISSEL, OF OAKLAND, CALIFORNIA.

LOCKING DEVICE FOR LEVERS.

1,292,548.

Specification of Letters Patent. Patented Jan. 28, 1919.

Application filed November 15, 1917. Serial No. 202,233.

To all whom it may concern:

Be it known that I, ROBERT G. WEISSEL, a citizen of the United States, residing at Oakland, in the county of Alameda and State of California, have invented certain new and useful Improvements in Locking Devices for Levers, of which the following is a specification.

The present invention relates to an improvement in lever locking devices, more particularly to that type set forth in Letters Patent No. 1,235,863 granted to me August 7, 1917.

In my present invention I have simplified the construction illustrated in my former patent, by eliminating one element thereof, and by so doing overcoming lost motion and considerable wear between the operative parts of the construction, namely the locking bolt and the bolt operating lever. By my improved construction I am enabled to more cheaply manufacture my improved lock and owing to the same being constructed of less parts, an efficient working of the same at all times is assured.

To more fully comprehend the invention, reference is directed to the accompanying drawings, wherein—

Figure 1 is a view in rear elevation of the preferred embodiment of my invention, illustrated as being mounted on a lever with the parts in locked position.

Fig. 2 is a sectional view taken on line 2—2 of Fig. 1.

Referring more particularly to the several views of the drawings, wherein like characters of reference designate corresponding parts,—1 indicates a suitable lever which extends through a guide plate 2 slotted as at 3 for the guiding of the lever and provided with a stop opening 4 for receiving the locking bolt of the lock mechanism when it is desired to prevent operative movement of the lever relative to its guide plate.

My improved lock consists of the side plates 5 connected at their front end by a transverse plate 6 and at their top by a member 7, the plates 5 and 6 and member 7 providing a lock casing having the offset portion 8 at one edge thereof.

Vertically movable within the lock casing is a suitable locking bolt 9 having an offset portion 10 and a vertical portion 11 formed on its rear face with a suitable rack 12. The upper end of the portion 11 is provided with a lip 13 between which and a corresponding

lip 14 extending inwardly from the front wall 6 is disposed a coiled spring 15 for normally maintaining said bolt 9 in its retracted position within the lock casing. The locking bolt 9 is guided in its vertical movement within the casing by a suitable securing member 16 passing through the walls 5 of the casing and through the lever for attaching the lower end of the casing thereto, said member 16 contacting with the rear face of the vertical portion 11 of the locking bolt 9 and maintaining the front wall 17 of the offset portion 10 of the bolt 9 in contact with the inner face of the offset portion of 70 the front wall 6 of the casing.

A bolt operating lever 18 is fulcrumed on a pin 19 which is disposed in rear of the vertical portion 11 of the bolt 9, and which connects the plates 5, said operating lever being 75 provided on its outer surface adjacent its fulcrum with suitable teeth 20 providing a pinion for engaging the tooth rack 12.

The bolt operating lever is capable of swinging movement in its fixed fulcrum 19 80 to either raise or lower the locking bolt 9, the outer end thereof being provided with a recess 21. When the lever 18 is in its uppermost position with its free end lying between the plates 5 and operating the bolt 9 85 to force the lower end thereof into the opening or recess 4, it is adapted to be engaged by a lock controlled latch 22 slidably mounted within a key controlled lock casing 23. The latch 22 is adapted to be drawn 90 downwardly within the casing 23 by any suitable mechanism operated by a controlling key 24, and on the release of said latch from the recess 21 a plunger 25 pressed outwardly by a spring 26 throws the free end 95 of the lever 18 from co-operation relative with the latch 22 and the spring 15 also assists in raising the lower end of the locking bolt 9 from the opening for causing the rotation of the lever on its fulcrum 19 to swing 100 the free end thereof downwardly from the position as in Fig. 2 to a position to lie adjacent the vertical portion 11 of the locking bolt 9.

A suitable securing member 26' passing 105 through the top member 7 secures the upper end of the casing to the lever and to prevent dust and grit from entering the key opening of the key controlled lock casing 23, and to conceal said opening an escutcheon 110 plate 27 is positioned over the same.

It is understood that my improved lever

lock while being illustrated to connect with a lever capable of operative movement within a guide slot, the same is adapted for attachment to any type of lever just so long as there is provided a stationary portion for engagement by the locking bolt when the same is moved to operative position.

Having thus described my invention, what I claim as new and desire to protect by Letters Patent is:—

A lock for a movable lever comprising a casing open at one side and provided at the opposite side near its base with an offset portion, a longitudinally movable locking bolt 15 mounted within the casing and having an offset locking portion, the body of said bolt being provided on one edge with a rack, a locking bolt operating lever having a fixed fulcrum at one end within the casing, said 20 fulcrumed end formed peripherally with teeth engaging the rack of said locking bolt and providing a pinion therefor, said lever provided at its opposite end with a laterally disposed tongue formed with a depression in 25 its under surface, a spring lock mechanism

within said casing and facing toward the open side thereof and with which said tongue is adapted to engage on the movement of said bolt operating lever to move the locking bolt to operative position, a spring 30 pressed plunger engageable by said tongue and movable toward the open side of said casing and adapted for forcing said tongue from said lock mechanism on the release of said mechanism, said locking bolt body being provided at its upper edge with a lateral flange extending laterally from the side thereof opposite to said rack, said casing provided adjacent said offset with a laterally extended flange and a spring co-operating 40 with said bolt and casing flanges for normally maintaining said bolt in its retracted position.

In testimony whereof I have signed my name to this specification in the presence 45 of the subscribing witness.

ROBERT G. WEISSEL.
